UNITED STATES PATENT OFFICE

JOHN D. DURANT, OF CLEVELAND, OHIO

THERMOSTATIC CIRCULATION CONTROL

Application filed March 19, 1928. Serial No. 262,805.

This invention relates to the control of the cooling circulation in internal combustion engines and the like.

The objects of the invention are to provide a simple, inexpensive and positively operating form of mechanism which can be readily installed in the present-day circulating systems and which will operate surely and safely to control the circulation in accordance with temperature changes.

A special important feature of the invention is the utilization of a Bourdon tube as the control element.

Other novel features relate to the mounting of the Bourdon tube and its method of operation, etc.

Various other novel features of the invention will appear as the specification proceeds.

The drawings accompanying and forming part of this specification illustrate certain practical embodiments of the invention, but it should be understood that structural changes may be made without departure from the true spirit and scope of the invention as hereinafter defined and broadly claimed.

Figure 1 is a broken sectional view of the head portion of an internal combustion engine illustrating the invention as controlling the return flow from the motor block, the valve being shown closed by the Bourdon tube to restrict the circulation from the motor block.

Figure 2 is an enlarged broken sectional view of the thermostat.

Figure 3 is a bottom plan view of the same with the Bourdon tube broken away and appearing partly in section.

Figure 4 is an enlarged broken sectional view of the adjustable link by which the tube is connected with the valve or shutter. Figure 5 is a sectional view illustrating a modified form of the invention.

In Figure 1, a part of a motor head is indicated at 6, having a return water passage 7 therein, opening downwardly into the water circulation chamber and opening upwardly into the return flow fitting 8 which is usually connected by hose or the like with the top of

the radiator. This return fitting is shown bolted in place on the motor head by bolts 9.

The circulation control comprises a sleeve-like member 10 shown in Figures 1 and 2 as having a base flange 11 caught beneath the flange 12 of the return fitting and made tight by a suitable gasket 13, said sleeve having a vane or valve 14, pivoted therein at 15 and connected by a link 16 with a Bourdon tube 17 which is affixed or secured to the base flange.

The link 16 is shown pivoted at 19 within a cup or cavity 20 pressed in the face of the valve and as pivoted at its opposite end at 21 to the free end of the Bourdon tube. 65

Adjustment in the length of the link and hence in the relation between the Bourdon tube and valve is provided for in the illustration by journaling a nut 22 in the angularly turned portion 23 of the link and engaging in the nut, the threaded shank of the pivot stud 24. The head portion 25 of this pivot stud is pivotally engaged on the pivot pin 21 and is shown as confined between the cheeks 26 which carry the pivot pin, said cheeks being formed by angularly turned extensions of a sheet metal filler piece 27 which is soldered or otherwise secured as a closure plug in the free end of the Bourdon tube. 70 The projecting back portion 28 of this closure piece by engagement with the wall of the mounting collar, as indicated in broken lines, Figure 2, is adapted to serve as a stop limiting the expanding movement of the tube and hence the extent of opening of the valve. 80

It will be evident that by turning the adjusting nut the effective length of the pivot stud may be made greater or less and hence the overall length of the link, the distance between the two pivots 19 and 21 may be determined at will. 85

The Bourdon tube is shown as detachably mounted by means of a special base piece 29, secured flat against the under side of the base flange by screws 30 and having a seat 31 in which the base end of the tube is rigidly secured. A screw plug is shown at 32, having a seat in the under face of the base piece and serving as a plug closing the base end of the tube. This con- 95

struction, it will be seen, permits the tube to be filled with the expansible fluid and to be tested for its operation before it is mounted or attached to the valve. This construction

5 provides for the ready substitution of one Bourdon tube for another and renders it possible to make quick repairs.

The valve illustrated is of generally oval shape with oppositely bevelled end edges to 10 closely fit in the substantially circular sleeve in the closed position indicated in Figure 2 and the link is preferably so adjusted in length that when the tube reaches the limit of its expanding movement, the valve will be fully open, as shown in the broken lines, Figure 2.

The screw plug which closes the end of the tube is entered at the back of the tube base and 20 is covered and fully protected when the base is mounted on the main support. The loop or bend 33 in the body of the link enables the link to be bent, if necessary, to adjust its length or to bring the rotatable adjusting nut into position to properly receive the screw shank of the pivot stud. This adjustment may be made such as to 25 "cant" the nut sufficiently so that it will bind on the stud and hence form a frictional lock therewith, preventing accidental turning of the nut after the proper adjustment has been made, or the nut may be soldered in the adjusted position.

The Bourdon tube is fixed rigidly to the support at its base end and curves downwardly into the circulating water space of 30 the motor head so as to be directly subjected to the heat conditions in the block of the motor, and the parts are so related that at subnormal circulation temperatures for the 35 motor, the valve will be held closed by the closing thrust of the Bourdon tube and will be shifted to the open position as the circulating water temperature reaches a normal or proper operating heat. In the fully open 40 condition it will be seen that the controlling device offers practically no obstruction to the free flow of circulating fluid. The device takes up but little room and may be readily installed in the average circulating system without any or very little change. The 45 Bourdon tube is especially sensitive to changes in temperature and is powerful enough in its action to insure complete closing and positive opening of the circulation 50 valve.

The form of the invention illustrated in Figure 5 has been developed to control a special by-pass provided in the head of certain motors. This by-pass is indicated at 55 and is intended for use in the "warming up" period of the motor when the cooling effect of the radiator is not required. After the motor is properly warmed, the by-pass should be closed and this is effected in the 60 illustration by a link 35 dependent from the

main valve 14 by pivot connection 36 and carrying at its lower end a valve 37 adapted to engage the valve seat 38 at the mouth of the by-pass.

The broken lines show how when the Bourdon tube opens up the main circulation valve 14, the supplemental valve 37 engages its seat to close off the by-pass. The link 35 is shown as arched at 39 to pass about the Bourdon tube and bring the valve 37 into position for engagement with its seat.

The thermostat structure in the last form is shown as supported in position over the water passages in the head of the motor block by a sleeve 40 within the fitting 8, having an inturned flange 41 at its upper end to which the flange 11 of the thermostat sleeve is secured by bolts 42.

The pivot fitting on the end of the Bourdon tube is illustrated in this last form as 45 having a collar portion 27' clasped about the flattened end of the tube and secured as by means of solder, the same soldering operation serving to seal the flattened end of the tube as indicated at 43.

What is claimed is:

1. In combination with a flow conduit of the cooling circulation system of an internal combustion engine, a thermostatic circulation control device mounted as a unit within said conduit and comprising a sleeve-like member defining the flow passage and having an outstanding flange by which the unit is mounted in the conduit and serving as a closure to the conduit to enforce flow through the sleeve member, a swinging valve closure for the sleeve member, a Bourdon tube fixedly supported at one end as a part of the unit, said Bourdon tube being of no greater overall dimensions than the outstanding flange of the unit, so as to enter freely in the circulation conduit and be subjected to the full influence of the cooling fluid closed off by the mounting flange and a link having one end pivoted directly to the free end of the Bourdon tube and having its opposite end pivoted directly to the swinging closure at a point closely adjacent the pivotal mounting of the swinging closure, whereby comparatively small movements of the Bourdon tube will be directly communicated to the swinging closure and will be effective to impart greater movements to said closure.

2. A combination as in the preceding claim, in which the sleeve member is arranged vertically, the mounting flange is arranged horizontally with the Bourdon tube below the same and in which the swinging closure stands in an inclined position in the closed relation, so that the movements of the same from fully closed to fully open position need be only through a small arc.

3. A thermostatic circulation control unit, comprising a tubular member providing a flow passage and having a surrounding an-

nular flange for mounting the same in the circulation system of an internal combustion engine, a valve pivotally mounted in said tubular member, a Bourdon tube supported at one end by the tubular member and a link pivoted at one end to the valve and having its opposite end pivotally connected with the free end of the Bourdon tube, whereby said Bourdon tube will be effective to directly and positively shift the valve in both opening and closing movements.

4. A thermostatic circulation control unit, comprising a tubular member providing a flow passage and having a surrounding annular flange for mounting the same in the circulation system of an internal combustion engine, a valve pivotally mounted in said tubular member, a Bourdon tube supported at one end by the tubular member, a link pivoted at one end to the valve and having its opposite end pivotally connected with the free end of the Bourdon tube, whereby said Bourdon tube will be effective to directly and positively shift the valve in both opening and closing movements, said tubular member being arranged substantially upright and the supporting flange standing out substantially horizontal thereto, the Bourdon tube being supported from the lower end of the tubular member so as to occupy a clear circulation space below the tubular member and beneath the supporting flange.

In testimony whereof I affix my signature.
JOHN D. DURANT.
